METHOD AND APPARATUS FOR FORMING
AUTOMOBILE SIDE RAILS

Ernest Riemenschneider, Cleveland, Ohio, assignor to The Midland Steel Products Company, Cleveland, Ohio, a corporation of Ohio

Application December 16, 1933, Serial No. 702,732

14 Claims. (Cl. 113—33)

This invention relates to a process and apparatus for producing articles from continuous strip stock, portions of which automatically come to a stop for operations thereon while other portions 5 travel continuously.

This invention has special reference to the practice of greater economy in the production of completely closed box section side rails having apertures provided in various portions thereof 10 for the attachment of other parts of the motor vehicle and frame before the rail is formed into closed box section thereby obviating the necessity of providing special equipment for the provision of such openings after formation of the 15 rail into such box section. The invention is also susceptible of use for the continuous production of side rails of other than completely closed box-section and includes means for simultaneously developing the contour of the ends of the rails 20 during the perforating operation.

A further object of the invention is to produce a multiplicity of side rails continuously and almost completely formed while a plurality of rails exist in the form of a continuous strip or 25 other form as it issues from the apparatus, requiring only the separation of the independent rails and simple finishing operations to give the rail final contour.

Another object of the invention is to provide a 30 process and apparatus for producing a plurality of side rails from a continuous strip upon which certain operations are performed while the stock moves continuously and on which other operations are performed during cessation of the feed 35 of the stock; these two operations being correlated by means providing sufficient slack in the strip to permit continuous travel of a portion of the strip while another portion thereof has its movements interrupted.

40 Other objects and advantages of the invention will become apparent during the course of the following description.

In the accompanying drawing forming a part 45 of the descriptive matter and wherein like numerals are employed to designate like parts throughout the several views,

Fig. 1 is a diagrammatic side elevation of the apparatus showing the essential steps for carrying out the herein described process,

50 Fig. 2 is an enlarged fragmentary plan of a portion of the strip stock after passing through a portion of the apparatus,

Fig. 3 is a series of section showing the form 55 imparted to the strip during its movement through several passes of forming rolls,

Fig. 4 is a transverse section taken on the line 4—4 of Fig. 1.

Fig. 5 is an enlarged transverse section taken on the line 5—5 of Fig. 1.

Fig. 6 is a fragmentary perspective of a portion 5 of the perforated and formed strip showing the preformed adjacent ends of a pair of rails prior to their separation.

Referring now more specifically to the drawing, the numeral 10 designates a coil or reel of 10 light gauge steel strip stock freely rotatably mounted in a position to deliver the strip across the elongated bed 11 of a perforating and shearing press. The press has a vertically movable ram carrying a multiplicity of punches 13 to 15 provide the strip 10 with properly positioned apertures or holes 15, and also has a cutting or slitting punch 14 at the end of the ram to slit or cut the strip transversely with a substantially X-shaped incision 16, as shown in Fig. 2 upon 20 each reciprocation of the ram. This incision may be of any desired developed shape to provide the ends of each rail section of the strip with a suitable contour when the blank is formed up into substantially a closed box-section side rail. 25

Adjacent the delivery end of the perforating press, is a pair of super-imposed knurled feed rolls 17, which engage opposite surfaces of the strip 10 at the margins thereof for drawing the strip across the bed of the press. These rolls 30 are geared together to rotate in unison and are spaced so as to firmly grip the strip for attaining a positive feed thereof. The rolls 17 are preferably of a circumference to make two or three complete revolutions for drawing a sufficient 35 length of the strip across the bed of the press to form a single side rail. Any suitable means may be provided for causing the rolls 17 to periodically cease rotation when a predetermined length of the strip has been drawn across the bed 40 and to remain idle for a sufficient length of time to permit the ram 12 of the press to perforate the blank and elevate to clear the stock. The movement of the ram 12 may be manually controlled or automatically controlled from the rolls 45 17 with suitable mechanism whereby the ram 13 does not descend with its perforating dies to perforate the strip until the rolls 17 stop. In the present embodiment and for purposes of illustration only, a gear rotatable with the lower roll 50 17 is shown meshing with a gear 18 of an electric motor 19 to drive the rolls the requisite number 22 which controls the starting and stopping of revolutions to draw the requisite length of strip across the bed of the press. 55

A pair of rolls 24 have intermeshing gears, the lower of which meshes with a gear 26 of a continuously operating motor 21. The armature shaft or gear may be provided with means cooperating with an automatically controlled switch 22 which controls the starting and stopping of motor 19, although the latter may be controlled manually or otherwise than illustrated. These rolls 24 constitute the first pass of a rolling mill 10 25 designed to bend the flat strip stock through the various stages illustrated in Fig. 3 to form the strip into hollow section or substantially that shown by the section 28 of Fig. 3 wherein the two longitudinal margins of the strip are not 15 brought into contact but are permitted to remain in slightly spaced relation before entering the edge spacing and welding apparatus to be presently described. In its passage through the rolling mill, the strip 18 is bent along the dotted lines 20 27 shown in Fig. 2 to be formed into hollow section and it will be noted that the ends of the incision 16 stop at approximately the outer bend lines 27 whereby the continuity of the strip remains and can be drawn through the apparatus until it is welded along the longitudinal margins 28 to form the desired section. The strip may be moved through the rolling mill by any one or more pairs of the rolls 29 or by means external to the rolling mill, but in any event the strip 30 from the press is guided into the rolling mill between a pair of idler rolls 38 at the end thereof. Obviously, the speed of movement of the strip through the rolling mill or the surface speed of the rolls 29 is co-related with the surface speed 35 of the rolls 17 in order to maintain a predetermined degree of slack stock 31 between the press of the rolling mill whereby the latter can continuously operate while the strip on the bed of the press 11 remains stationary to receive the necessary perforations and incision while the rolls 40 17 remain at a standstill. This slack portion 31 of the strip is maintained by its passage over an idler roll 32 which exerts a constant upward pull 45 on the slack portion of the strip by any suitable means such for example as a cable 32 being suspended over a sheave wheel with a counterweight 33 attached to the end thereof to maintain the elevation of the pulley 32 and proper tension upon the slack portion of the strip. When the rolls 50 17 are automatically stopped to enable the press to make the requisite perforations in the length of the strip, the continuous operation of the rolling mill uses up a portion of the slack causing a lowering of the pulley 32 and of the slack portion 55 to approximately the dotted lines 34 shown in Fig. 1 and just before this slack has been taken up the rolls 17 automatically start operation again upon elevation of the perforating punch to move another predetermined length of the strip across 60 the bed of the press while more slack is being provided.

After being brought to the box form 28 shown in Fig. 3, the formed section is moved through a confining throat 35 which moves the edges of the hollow section into substantial abutment thereby causing these edges to fulcrum on a spreader roll 36 having a circumferential rib 37 as shown in Fig. 4 which causes the seam to open up a predetermined distance as it enters under a welding instrumentality 38 as described in my co-pending application Serial No. 680,481. This welding instrumentality may be of any type but is preferably of the atomic hydrogen type including a plurality of atomic hydrogen units 39 adapted to 75 provide sufficient liquid metal on the spaced apart

edges of the stock to assure complete penetration of the weld as the edges of the stock are moved together by the effect of side pressure rolls 40 engaging opposite sides of the box section as illustrated in Fig. 5. Top and bottom rolls 41 5 and 42 are provided to maintain the contour of the box section and to force the welded portions into the same plane. Obviously, the section formed by the apparatus may be tubular or otherwise. 10

If preferred, the tubular formed stock after being welded is run through a series of straightening rolls 43 from where it passes to a cut-off station 44, where the incisions 16 are completed to separate the stock into individual section of 15 predetermined length, preferably of a length to 20 constitute a side rail of an automotive vehicle.

When the strip is formed into box section, the intermediate portion 45 of the incision extends transversely across the bottom of the box section 25 while the two arms 46 at either side of the intermediate section diverge upwardly as shown in Fig. 6 for the full depth of the sides of the rail. The ends of these incisions 46 terminate approximately at the upper corners of the box section as shown in Fig. 6 and the individual rails are severed by cutting transversely of the box section along two lines 47 by means of electric 30 torches or otherwise. If it is desired to accomplish this separation automatically, an automatic 35 cut-off 48 embodying saws or cutters 49 may have its movement controlled so as to grip the stock adjacent the division points and move along with the stock as it continues its travel through the apparatus while the saws or cutters 49 are making 40 final incisions 47 to separate the stock into individual sections. After each severance, the automatic cutoff automatically moves to the left of Fig. 1 to grip the stock at the next succeeding 45 point of division to again start cutting along the lines 47 as the stock moves to the right of the figure.

Instead of separating the individual rails by cutting incisions 45 and 46 all the way through the strip and subsequently cutting apart along 45 the lines 47, they may be separated by cutting along these or other lines only part way through the thickness of the strip to provide weakened lines of division. Along these weakened lines there is only sufficient material left by which succeeding sections or rails can be pulled or propelled, one by the other, through the entire machine. However, these lines are only of such strength that they will break apart as the finished 50 box section stock is guided over means causing 55 rupture along the weakened lines and separation of the rails. Such means may be suitable fulcrum member against which the box section stock is pressed with suitable pressure means exerting pressure at points on opposite sides of 60 the weakened line to be broken and in a direction toward the fulcrum. In the present arrangement of weakened lines, the fulcrum is applied under the line 45 and the stock is bent down over the same at opposite sides of the fulcrum, or the latter may be moved upwardly against the division line 45 to cause breaking stress to be augmented by the inclined lines of division 46. In some cases, part of the division lines will be cut 65 all the way through the stock and the remainder 70 of such lines will only be cut part of the way through the thickness of the stock.

After the individual straight box-sections have been obtained from the apparatus, they may be shaped to provide each rail section with forward 75

- and rear kickup portions in a suitable tube bending mill or mechanism to provide the completed rail having the necessary apertures in opposite sides thereof and in registration in some instances 5 for the attachment of other parts of the motor vehicle and frame parts. While the process has been described for the production of automobile side rails, it is obvious that the other articles can be produced by this method.
- 10 It is to be understood that various changes in the process and apparatus may be made without departing from the scope of the appended claims.

I claim:

- 15 1. An apparatus for producing articles from continuous strip stock including a reciprocatory intermittently operated press into which the strip is intermittently fed and slack is produced on the exit side of the press, a continuously operating mechanism for continually moving the strip away from the slack stock, a counter weighted roll between the press and mechanism over which the strip passes to maintain the slack strip in condition to compensate for the intervals of non- 20 travel of portions of the strip in advance of the roll while undergoing operations in the press whereby said mechanism on the opposite side of said counter weighted roll continuously moves the strip therethrough.
- 25 2. The method of continuously forming tubular articles from continuous strip stock, consisting of weakening the strip transversely at intervals to provide a plurality of individual sections of stock joined by continuous longitudinal uninterrupted 30 marginal edges whereby one section is propelled along by its adjacent section, bending the stock into tubular form while the sections are joined and presenting two contiguous uncut edges throughout the length of the strip and then welding said uncut edges together.
- 35 3. The method of continuously forming tubular articles from continuous strip stock, consisting of providing the strip stock transversely at intervals with substantially X-shaped slits terminating at spaced intervals from the longitudinal edges of the strip, forming the slited strip stock into substantially tubular cross section whereby the unslotted margins of the strip form substantially one side of the tubular section, welding the 40 longitudinal margins of the strip together, and then separating the portions of the strip between the slits by severing the strip along lines extending through the ends of the X-shaped slits.
- 45 4. An apparatus for producing tubular metal articles from continuous metal strip stock including an intermittently operated blanking press adapted to cut the stock, feed mechanism for intermittently moving predetermined lengths of stock through said press at intervals 50 for producing a quantity of slack stock at the exit side of the press after each stoppage of the movement of the stock, a drive mechanism for said feed mechanism, and continuously operating means for continuously forming the strip 55 stock from the slack stock into tubular form, and means operable by said continuously operating means for intermittently operating the drive mechanism for the feed mechanism to move the stock through the press.
- 60 5. An apparatus for producing automobile side rails from continuous metal strip stock, including an intermittently operable part for cutting the stock, means for holding strip stock, feed means for moving predetermined lengths of the stock 65 from said means through the press and produc-

ing slack stock at the exit side of the press, and continuously operating means for continuously forming the stock into tubular section with its marginal edges adjacent each other and for intermittently operating the aforesaid feed means. 5

6. An apparatus for producing automobile side rails from continuous metal strip stock including an intermittently operable press, means for holding strip stock, feed means for moving predetermined lengths of the stock from said holding 10 means through the press and for producing slack stock at the exit side of the press, continuously operating means for forming the strip stock from the slack into tubular form with the longitudinal marginal edges of the stock adjacent one another, and for intermittently operating the aforesaid feed means, slack stock maintaining means between the press and forming means, welding means for joining said marginal edges of the strip stock after formation, and 15 means for separating the formed stock into predetermined lengths.

7. An apparatus for producing metallic articles from continuous strip stock including an intermittently operable press for making cuts 20 transversely of the stock, intermittently operable feed means for moving predetermined lengths of the stock through the press and producing slack stock on the exit side of the press, continuously operating means for forming the strip 25 stock from the slack stock into tubular form with the longitudinal marginal edges of the stock adjacent one another, welding means for joining said marginal edges of the strip stock after formation into tubular form, and means for completing 30 the cuts in the stock made by the press for separating the formed stock into separate tubular articles.

8. An apparatus for producing tubular metal stock from flat strip stock comprising means for 35 cutting openings in the flat stock having continuous straight uninterrupted longitudinal edges, means for progressively forming the flat strip stock into tubular form with its longitudinal marginal edges adjacent each other, and means 40 for continuously welding said uninterrupted marginal edges of the strip together.

9. The method of forming tubular metal pieces by continuous welding methods, including producing laterally slotted flat strip stock having 45 continuous uninterrupted longitudinal margins, shaping and continuously welding said margins of said stock so as to effect a continuous production of circumferentially slotted tubular welded stock, and then cutting the portions of said stock 50 circumferentially separating its slot.

10. A method of forming automobile side rails from continuous strip metal stock consisting of first intermittently moving the strip to blank and perforate the strip and to produce slack in the 55 strip beyond the point where it is blanked, perforating and blanking the strip during each stop of the strip, continuously moving the blanked continuous strip from said slack stock through a continuously operating forming device, and 60 forming the continuously moving portion of the strip into hollow section with its longitudinal margins adjacent each other by continuously feeding the strip from said slack through said 65 continuously operating forming device. 70

11. A method of forming automobile side rails from continuous strip metal stock consisting of first intermittently moving the strip stock across the bed of an intermittently operable device whereby the stock is intermittently stopped and 75

- 5 a quantity of slack stock is produced at a point beyond the exit of said device, cutting the strip during each stop period, continuously moving the strip from said slack portion into a continuously operating means, and continuously forming said strip stock into hollow section with its longitudinal margins adjacent each other by continuously feeding part of the strip from said slack into said continuously operating means.
- 10 12. A method of forming automobile side rails from continuous strip metal stock consisting of first intermittently moving the strip stock across the bed of an intermittently operable device whereby the stock is intermittently stopped and a quantity of slack stock is produced at a point beyond the exit of said device, cutting the strip during each stop period, continuously moving the strip from said slack portion into a continuously operating means, and continuously welding the adjacent longitudinal margins to form the strip into hollow section.
- 15 13. The method of continuously forming hollow articles from continuous strip stock, consisting of providing the strip stock transversely at intervals with slits terminating at spaced inter-
- 20 vals from the longitudinal edges of the strip, forming the slotted strip stock into hollow cross section whereby the unslit margins of the strip form substantially one side of the hollow section, welding the longitudinal margins of the 5 strip together, and then separating the portions of the strip between the slits by severing the strip along lines extending through the ends of said slits.
- 25 14. An apparatus for producing articles from 10 continuous strip stock including an intermittently operated press for intermittently cutting the strip stock, a continuously operating mechanism for continuously moving the strip away from the press, feeding rolls for drawing the stock through 15 the press at intervals and producing slack at the exit side of the press, a counter weighted roll between the feeding rolls and said mechanism over which the strip passes to maintain a quantity of slack in the strip stock, drive means 20 for said continuously operating mechanism, and periodically operated means for the feeding rolls operated from said drive means of said continuously operating mechanism.

ERNEST RIEMENSCHNEIDER. 25
